UNITED STATES PATENT OFFICE.

JOSEPH H. CHOQUETTE, OF FALL RIVER, MASSACHUSETTS.

ADJUSTABLE DRESS-CHART.

SPECIFICATION forming part of Letters Patent No. 700,739, dated May 27, 1902.

Application filed December 12, 1901. Serial No. 85,722. (No model.)

To all whom it may concern:

Be it known that I, JOSEPH H. CHOQUETTE, a citizen of the United States, residing at Fall River, in the county of Bristol and State of Massachusetts, have invented certain new and useful Improvements in Adjustable Dress-Charts; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to adjustable patterns for ladies' garments; and it consists in certain forms hereinafter described, composing templets united by rivets and slots, so that the several parts can be adjusted to correspond with the measurements of any particular person.

20 The object of my invention is to simplify the devices of this character heretofore proposed by reducing the number of parts while at the same time providing for a greater range of adjustment.

In the accompanying drawings, Figure 1 is a plan view of the form for the front part of a lady's bodice. Fig. 1^a shows the rear side 30 of the upper portion of the same. Fig. 1^b shows the normal position of certain parts. Fig. 2 shows the form for the under-arm piece of the bodice; Fig. 3, the form for the back of the bodice; Fig. 4, the form for the 35 side back-piece of the bodice; Fig. 5, the form for the sleeve.

The several parts or templets which make up the forms are constructed of thin stiff material, preferably cardboard. Metallic rivets and studs are used to unite the templets, and the slots in which the studs slide are edged with metal while the holes for dotting points of measurement are bushed with metal. The edges of slender portions of the templets 40 may be stiffened with a metal binding.

Figs. 1 and 1^a illustrate the form for laying out the front of a bodice. It consists of ten templets of suitable shape overlapped and adjustably connected together. The main 45 templet A has a curved front edge a, bearing a scale of inches a' to indicate the length of the front. At the upper end is a curved

edge a², which forms part of the neck-pattern. The top edge a³ is straight, while the edge a⁴ opposite a² is shaped on a concave 55 curve, meeting at its lower end a convex curve a⁵, extending up from a nearly-straight edge a⁶, substantially parallel with the edge a. The lower end of the templet A has a deep-pointed notch a⁷, having two legs in 60 which are formed lengthwise slots a⁸. A slot a⁹ runs diagonally across the templet from near the upper end of the edge a to near the lower end of the edge a⁴. Short parallel slots a¹⁰ lie near the upper portions of the edges 65 a² a⁴. Along the slots a⁹ a¹⁰ are graduations marked for various breast-measures. The templet A' is L-shaped. Its upright arm a¹¹ has a slightly-curved front edge a¹², forming a continuation of the edge a of plate A. The lower edge a¹³ of the plate A' is straight and at substantially right angles to the edge a¹¹. From the upper side of the horizontal arm of the L rises an arm a¹⁴. In the arms a¹¹ a¹⁴ are lengthwise slots a¹⁵. Rivets a¹⁶ in the 70 plates A A' pass through the slots a⁸ and a¹⁵ and permit a sliding adjustment of one plate on the other. The opening between the arms a¹¹ a¹⁴ forms with the notch a⁷ the pattern for one of the darts in the lower end of the 75 bodice. In the horizontal arm of the L is a lengthwise slot a¹⁷ with graduations indicating the difference between bust and waist measure. The second dart is outlined by the edge a⁶ of the plate A and the arm a¹⁴, the upper edge of the horizontal arm of the plate A', and the adjacent edges of the plates B B', the upper of which is hinged at b to the plate A, while the lower is adjustable along the upper by slots b' and rivets b². The plate B' 80 is also L-shaped, the end of its horizontal arm having a rivet b³, sliding in the slot a¹⁷. Parallel with the lower edge b⁴ of the plate B' is a slot b⁵, graduated to indicate the 85 waist-measure of the bodice. At the upper end of the plate B are graduations b⁶, indicating the bust-measure and denoting the points for the top of the dart. The width of the dart can be varied by swinging the plates B B' on the pivot b. The size of the neck-opening 90 can be varied by adjusting a templet C, which is substantially rectangular in shape and has rivets c sliding in the slots a¹⁰. In the plate C is a horizontal slot c', co-operating 95

with a similar slot d in the adjacent plate D and permitting a relative adjustment of them to suit the length of the shoulder-seam. The plate D has a straight upper edge d' , converging curving side edges d^2 , and a lengthwise slightly-curved slot d^3 , permitting its adjustment with reference to a plate E, which is substantially crescent-shaped and is pivoted at e to a slightly-curved plate F, having parallel sides and provided with a lengthwise slot f . Rivets f' in the plates F and A permit the plate F to be slid along the slot a^9 . At the outer end of the plate F is pivoted a plate G, to which is adjustably attached a plate G', both having slightly-curved edges g^1 and longitudinal slots $g^2 g^3$. Graduations g^4 on the plate G indicate the under-arm length of the bodice. The lower end of the plate G' has a laterally-extending foot g^5 , carrying a rivet g^6 , sliding in the slot b^5 . In Fig. 1 the plates D E are shown pulled out to give a better idea of their shape. In use they lie about as shown in Fig. 1^b and form the pattern for the edge of the armhole.

Fig. 2 shows a plan view of the form for the under-arm piece of the bodice. It consists of four templets and is adjustable as to width and length. The templet H has a slightly-curved upper edge, parallel to which is a slot h . The side edges h' are gently curved, and a longitudinal slot h^2 co-operates with a similar slot i in the templet I to permit lengthwise adjustment according to the graduations h^3 . The lower end of the plate I flares somewhat and contains a transverse slot i' . The plates H' I' are very similar in shape to the plates H I and carry rivets $h^4 i^2$, sliding, respectively, in the slots $h i'$ for adjustment in width according to graduations, h^5 indicating bust-measure, and i^3 indicating waist-measure.

Fig. 3 illustrates the form for laying out the back. It is composed of six plates, all adjustable on each other. Plate K has a substantially straight edge k for the middle seam of the back. Its opposite edge k' diverges therefrom from the bottom upward on a curve until it meets the short upright edge k^2 , which connects with the oblique upper edge k^3 , defining the shoulder-seam and meeting the short top neck portion k^4 . A longitudinal slot k^5 enables a narrow plate K' to be slid up and down to give the right length to the middle seam. The lower end k^6 of the plate K' is flaring, as shown. Plates L L' M M' enable the dimensions of the back-form to be enlarged to different sizes. The plate L has two edges $l l'$, meeting at the same angle as the edges $k^3 k^4$. It carries rivets l^3 , sliding in slots l^7 , parallel with the edge k^4 , and graduated according to the bust-measure. The plate L' has one edge l^2 in line with the edge l' of the plate L and another edge l^8 parallel with the edge k^2 of the plate K. By means of slots l^4 in the plates L L', parallel with the edges $l l'$, and the connecting-rivets l^5 the length of the shoulder-seams can be adjusted.

A plate M of triangular shape with slightly-concave edge is connected with the plates K and L', having a slot m parallel with the slots l^4 and engaged by a rivet k^8 . Graduations m' along the slot m indicate bust-measure. A rivet m^2 in the plate M engages a slot l^6 parallel with the edge l^3 of the plate L'. A long narrow plate M', slightly curved, is pivoted at m^3 to the plate k' and is connected by slots m^4 and rivets m^5 with the plate M, so that the latter can be swung toward and away from the plate K and slid up and down lengthwise.

Fig. 4 illustrates the side back-form, very similar in shape and construction to the under-arm form shown in Fig. 2. It is composed of two long narrow plates N N', the latter having a pronounced curve in its edge n and running up to a point by reason of its sharply-oblique upper edge n' . A slot n^2 , co-operating with a rivet n^3 on the plate N, affords adjustment in width at the upper end of the form, the slot being graduated in bust-measures. At n^4 are graduations for setting the form to the proper under-arm length. The lower plates P P' are adjustable lengthwise of the plates N N' by slots $n^5 p$ and rivets $n^6 p'$. They have widened lower ends adjustable laterally by a slot p^2 and rivet p^3 to agree with the waist-measure.

Fig. 5 shows the sleeve-form, composed of nine templets, all having substantially parallel sides of nearly the same width, so that the upper part of a sleeve can be drafted by following the outside of the form and the under part by following the inside thereof. The upper plate R is crescent-shaped and has two longitudinal slots $r r'$, each graduated with armhole sizes, the graduations on each slot reading from the middle toward that end of the plate. An elbow-shaped plate S has one limb provided with the slot s , co-operating with the slot r to afford lengthwise adjustment of the plates R and S. The angle of the elbow-plate is connected by two slotted and lengthwise-adjustable curved plates T T' with the farther end of the plate R, the plates T T' being pivotally attached by rivets $t t'$, the latter of which slides in the slot r' . A plate U is pivotally attached by the rivet t' to the plate T'. A plate V, having a slightly-concave outer edge v , is adjustably attached by lengthwise slots and rivets to the plate S. A similar plate W, having a convex outer edge w , is similarly attached to the plate U. Lateral arms $v' w'$ on the plates V W are adjustably connected by the slot w^3 and rivet v^2 , the slot being graduated for the elbow-measure. Graduations w^4 , indicating the sleeve length, are made along the lengthwise slots in the plate W, running from the middle toward the ends of said plate. A short plate X enables the lower end of plate V to be extended, while an L-shaped plate Y, similarly extensible on the plate W, is also adjustably connected by slot y and rivet x with the plate X, the graduations y' being for the hand size. When draft

ing the outer or upper part of the sleeve, the outer edges of the plates R and S are followed, while in drafting the under part of the sleeve the edges of the plates T T' are followed.

5 Having thus described my invention, what I claim is—

1. A form for drafting a bodice-front, comprising the main templet A having the notch a^7 and the slots a^8, a^9, a^{10} , the plate A' having arms $a^{11} a^{14}$ slidably connected with the plate A and having the slots $a^{15} a^{17}$, the plate B, pivoted to the plate A and having the slot b , and the graduations b^6 , the plate B' having the slots b', b^5 and slidably connected with the plates A' and B', the plate C slidably connected with the plate A by the slots a^{10} , the plate D slidable transversely on the plate C and having the longitudinal slot d^8 , the plate E slidable on the plate D, the plate F slidable in the slot a^9 and pivotally connected with the plate E, the plate G pivotally attached to the plate F, and the plate G' slidably attached to the plate G and the plate B', the slots a^9, a^{10} and d being graduated for bust-measure, and the slot b^5 for waist-measure.

2. A form for drafting the back of a bodice, comprising the plate K, the plate K' slidable lengthwise thereon, the plate L slidable laterally on the plate K, the plate L' slidable

lengthwise on the plate L, the plate M slid- 30
able laterally on the plate K and in a length-
wise direction on the plate L', and the plate
M', pivoted to the plate K' and slidable on
the plate M, the adjustment of the plates L
and M being according to bust-measures. 35

3. A form for drafting sleeves for garments, comprising a crescent-shaped plate R, containing longitudinal slots r, r' , an elbow-shaped plate S having a longitudinal slot in each arm, two longitudinally - adjustable 40
curved plates T, T', pivotally attached to the plate S and pivotally and adjustably to the plate R, a plate U pivoted to the pivot of the plate T', plates V, W, adjustable respectively along the plates S and U, and each provided 45
with a lateral arm, said arms being adjustably connected to a short plate X constituting an adjustable extension of the plate V, and an L-shaped plate Y similarly adjustable on the plate W and having its lateral arm 50
adjustably connected with the plate X.

In testimony whereof I affix my signature in presence of two witnesses.

JOSEPH H. CHOQUETTE.
